(57) **CLAIM**

I claim the ornamental design for jointed swim bait fishing lure design, as shown and described.

DESCRIPTION

FIG. 1 is a top plan view of the jointed swim bait fishing lure design showing my new design;

FIG. 2 is a side elevation view thereof;

FIG. 3 is a bottom plan view thereof;

FIG. 4 is a front elevation view thereof;

FIG. 5 is a rear elevation view thereof; and,

FIG. 6 is a perspective view.

The broken lines in the drawings depict parts of the portion of fish bait design that are not part of the claim. The broken lines and the structures and features they depict form no part of the claimed design.
